SERVING FORK

Arthur Salm, Chicago, Ill., assignor to Arthur Salm Inc.,
Chicago, Ill., a corporation of Illinois

Application July 18, 1955, Serial No. 37,013

Term of patent 14 years

(Cl. D54—12)

Fig. 1 is a front view of the serving fork showing my new design;

Fig. 2 is a side elevational view thereof; and

Fig. 3 is a transverse sectional view of the ornamental design of Fig. 1, taken on the line 3—3 thereof.

I claim:

The ornamental design for a serving fork, substantially as shown.
